CLAIM

The ornamental design for a body armor, as shown and described.

DESCRIPTION

FIG. 1 is a front side perspective view of a body armor showing my new design;

FIG. 2 is a front side view thereof;

FIG. 3 is a back side view thereof;

FIG. 4 is a left side view thereof;

FIG. 5 is a right side view thereof;

FIG. 6 is a top elevational view thereof; and,

FIG. 7 is a bottom elevational view thereof.

The broken lines in the drawings depict portions of the body armor that are not part of the claimed design. Structures drawn in broken lines are included for the purpose of showing the design in a condition of use.
